UNITED STATES PATENT OFFICE.

ARTHUR M. ANDERSON, OF PRINCETON, ILLINOIS.

DISPLAY AND STORAGE CABINET.

1,054,959.

Specification of Letters Patent.

Patented Mar. 4, 1913.

Application filed February 29, 1912. Serial No. 680,656.

To all whom it may concern:

Be it known that I, ARTHUR M. ANDERSON, a citizen of the United States, residing at Princeton, in the county of Bureau and State of Illinois, have invented certain new and useful Improvements in Display and Storage Cabinets; and I do hereby declare the following to be a full, clear, and exact description of the invention, such as will enable others skilled in the art to which it appertains to make and use the same.

My invention relates to display cabinets, and it relates especially to an improved cabinet for displaying merchandise of various kinds and my object, among others, is to provide improved and efficient means for not only displaying the merchandise to the view of the customers, but also to safely house and protect them against detriment from dust and exposure.

A further object of my invention is to provide a plurality of improved holding devices or shelves, upon which various kinds of merchandise may be disposed within a suitable dust proof casing for the protection of the contents.

Other objects and advantages will be hereinafter made clearly apparent, reference being had to the accompanying drawings, in which,

Figure 1 shows my improved housing and display cabinet complete. Fig. 2 shows a detail view of supporting means for one of the shelves or auxiliary supporting rack.

Fig. 3 is a vertical central section through a portion of the cabinet. Fig. 4 is a detail perspective view of one of the carrying brackets for the shelves. Fig. 5 is a front or edge view of the brackets shown in Fig. 4,

and the controlling sprocket chain connected therewith. Fig. 6 is a detail view, showing one of the sprocket wheels and also showing three shelves and carrying brackets therefor.

Fig. 7 is a detail perspective view of the adjustable shelf supporting means shown in Fig. 2, and Figs. 8 and 9 show, respectively, a perspective and edge view of a slightly modified form of clamp from that shown in Figs. 2 and 7.

In order to conveniently refer to the various parts of my invention, numerals will be employed, the same numeral being applied to corresponding parts throughout the several views.

In materializing my invention, I provide a housing or case 1, of any preferred size

and shape, preferably provided with sliding glass doors, it being also understood that a plurality of receptacles or drawers 2 may also be provided in the base portion thereof if deemed desirable. Within the casing or housing thus or otherwise constructed, I mount, in any preferred and suitable manner, upon each side of the casing, a pair of sprocket wheels 3, one at the upper end and one at the lower end of the casing, as shown in Fig. 3. Coöperating with said wheels and carried thereby is a suitable form of sprocket chain 4, having properly formed links to engage the teeth 5 upon said sprocket wheels, and mounted upon said chain, by the means hereinafter described, are a plurality of shelf carrying brackets 6, each of which is substantially triangular in form and is provided, at its respective upper and lower ends and at opposite sides, with anti-friction rollers 7 and 8, as clearly set forth in Figs. 4 and 5, it being understood that any suitable form of anti-friction roller bearings may be adopted, if deemed desirable. The said brackets 6 are each provided with an outwardly extending socket member 9, in which is anchored a bolt or pivot pin 10, which latter extends through the tubular member 11 of one of the links of the sprocket chain 4, as illustrated in Figs. 5 and 6. The said brackets 6 are each provided upon their inner side and lower edge with a lip 12, designed to support a shelf member 13, which latter is permanently secured to the said lip section 12 in any preferred way, as by bolts 14, (see Fig. 5.) The said brackets are each provided with an anchoring seat 15, located preferably upon the under side of the supporting ledge or lip 12, the said member 15 having a threaded aperture in which is seated a tightening screw 16, the said screw being connected with a bridging or supporting wire or rod 17, adapted to extend to a similar tightening screw, (not shown.) Obviously the said bridging wire 17 is for the purpose of supporting the medial portion of the shelf 13.

In order that the plurality of shelves may be reliably maintained with the load thereon in a substantially horizontal plane, I have provided in each end of the casing a guide beam 18 and a trackway 19. The said trackway 19 at its upper and lower ends is of peculiar and special formation, inasmuch as at the upper end thereof (see Fig. 6), I have formed the curved sections 20, 21 and

22, each of which in turn coacts with and guides the anti-friction rollers 7 and 8. By reference to Fig. 6 it will be observed that the right hand anti-friction wheel 8 is bearing against the right hand trackway 19, and it is thence moved upward into contact with the curved guide 20. It is further seen that the right hand anti-friction wheel 7 is contacting with the guide beam 18 and will be brought into contact with the curved section 22 and thence moved downward into contact with the left hand trackway 19, while the anti-friction wheel 8 is brought into engagement first with the curved portion 18^a of the guide beam, and later into contact with the left hand vertical side thereof. The lower end of the trackway 19 is provided with similarly curved sections 23 and 24 for guiding the brackets as they pass under the lower wheel 3.

From the foregoing construction it will be seen that, inasmuch as the several shelf-carrying brackets are pivotally connected at their central part with the sprocket chain, and by reason of the guideways 19 and the member 18, the said shelves are at all times kept in a substantially horizontal plane, whereby the merchandise carried thereon will retain its proper position.

This my improved display cabinet is especially useful for the display and protection of hats, caps, gloves, shoes and other comparatively small articles.

The axle of the lower sprocket wheels is provided with a suitable extension upon which is mounted a handle or crank, whereby the shaft may be rotated for revolving the shelves through the casing and thereby bringing the upper shelves, and the merchandise contained thereon, downward into position for inspection; and, by continuing the operation, all of the merchandise may be readily brought into plain view.

At the lower end of the guide beam 18, I have provided a curved terminal 18^b, said terminal being curved oppositely from the upper curved end 18^a; the purpose of said curved terminal being to guide the anti-friction rollers, and to insure that the shelving will remain horizontal.

It will thus be seen that I have provided an improved and efficient means whereby various classes of merchandise may be effectively displayed and thoroughly protected from dust and other detrimental influences and, while I have described the preferred construction and combination of parts, I apprehend such equivalents and substitutes as may be regarded as falling fairly within the scope of my invention.

My cabinet may be provided with glass doors, as previously set forth, and I provide a counter-balance weight 25 therefor, said weight being supported by a suitable cable 26, extending around the pulley wheel 27,

mounted in any suitable manner, as by the bracket 28 at the top and interior of the casing, though obviously this same result may be accomplished by other proper means.

I have also provided an auxiliary form of shelving for the display of smaller articles, said shelving being illustrated in Fig. 1 and shown as being disposed upon the lower shelf and consists of the supporting standards 29 and the shelves 30 carried thereby. In Figs. 2, 7, 8 and 9, I have shown the preferred means for supporting the said shelving, wherein it will be seen that the supporting standards or rods 29 are provided with a gripping appliance or clamp, which it will be observed is preferably formed of a single piece of sheet metal.

In Figs. 8 and 9, I have shown the preferred form of construction of my improved clamp, which consists of a single piece of suitable sheet steel bent upon itself at the middle portion, as indicated by the numeral 31, said middle portion being curved to fit around the shelf carrying frame 32, the free ends of said sheet metal being then bent to form the members 33 and 34, which are disposed as normally separated from each other and are each provided with an aperture 35 to receive the supporting standard 29. The member 34, it will be observed, is provided with the terminal 36, which is bent at right angles so as to engage the outer end of the member 33, when said members are forced toward each other. The length of the terminal 36 is sufficient to insure that the openings 35 will be in true registration with each other to fit loosely around the standard 29 and move freely thereon. It therefore follows that when the pressure upon the members 33 and 34 is removed, the said members will at once separate from each other and grip the standard 29 and thereby hold the clamp in any adjusted position thereon.

In the modified form of clamping appliance shown in Figs. 2 and 7, the said clamp consists of a single piece of metal, which is first bent near its middle portion so as to form the tubular section 37, designed to fit around the frame section 32, when the end members of the metal forming said clamp are then bent backward against the tubular section 37 and left normally separated, each of said members being provided with an aperture of proper size to receive the standard 29 and bite securely against the same when released at the point where it is desired to dispose the supporting frame for the shelf.

Believing that the advantages and manner of constructing and using my invention have thus been made clearly apparent, further description is deemed unnecessary.

What I claim is:

1. In combination, a casing, a shaft rotat-

tably mounted in the casing, a pair of concentric sprocket wheels carried by the shaft, a second pair of sprocket wheels rotatably mounted in the respective planes of the first 5 said sprocket wheels, chains carried by the sprocket wheels, shelf-carrying brackets pivotally mounted on the chains, upper and lower rollers carried by the brackets, and a guide beam located in the plane of the axes 10 of the sprocket wheels and being adapted to contact with the upper rollers as the brackets move on one side of the guide beam and to contact with the lower rollers as the brackets move on the other side thereof for 15 guiding said brackets and retaining said shelves in substantially horizontal position at all times.

2. In a device of the character described, a casing, supporting wheels rotatably 20 mounted in the casing, flexible members car-

ried by the wheels, shelf-carrying brackets pivoted to the flexible members, each of the shelf-carrying brackets having guide rollers disposed on opposite sides of the pivotal connection of the bracket and flexible member, and a guide beam between the supporting wheels and in position for contacting with the guide rollers on one side of the pivotal connection when the shelves are carried on one side of the guide beam, and the 25 other rollers contacting with the other side of the guide beam when the shelves are carried on said other side of the guide beam.

In testimony whereof I have signed my name to this specification in the presence of 30 two subscribing witnesses.

ARTHUR M. ANDERSON.
